UNITED STATES PATENT OFFICE.

MOSES B. DISKIN, OF NEW YORK, N. Y.

BOX-MANDREL.

1,343,907.

Specification of Letters Patent. Patented June 22, 1920.

Application filed January 11, 1919. Serial No. 270,699.

To all whom it may concern:

Be it known that I, MOSES B. DISKIN, a citizen of the United States, residing at New York, in the county of New York and State of New York, have invented certain new and useful Improvements in Box-Mandrels; and I do hereby declare the following to be a full, clear, and exact description of the invention, such as will enable others skilled in the art to which it appertains to make and use the same.

The present invention relates to a mandrel or form for use in making paper, cardboard and similar boxes or containers, and it is the primary object of the invention to provide a novel and improved mandrel or form which is adjustable to various sizes, both in length and width.

Another object of the invention is the provision of a mandrel comprising sections slidably connected in a novel manner for the adjustment of the mandrel, and to render the same substantial in construction in the various adjustments.

A further object is the provision of a novel and improved mounting for the mandrel, permitting of the ready adjustment thereof, and enabling the parts to be firmly held in any adjusted position, such mounting permitting of independent adjustments of the mandrel for different lengths and widths.

A still further object is the provision of such a mounting for the mandrel located interiorly thereof and of such construction and so connected to the mandrel proper, that independent adjustments in both directions can be made, and the parts firmly clamped and held after adjustments have been made.

It is also the object of the invention to provide such a construction which is comparatively simple and inexpensive, as well as being practical and efficacious in use.

With the foregoing and other objects in view which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawing, wherein:

Figure 1 is a plan view of the improved mandrel.

Fig. 2 is a longitudinal section taken on the line 2—2 of Fig. 1, portions being shown in elevation.

Fig. 3 is a plan view of the central supporting block.

Fig. 4 is a plan view of one of the toggle levers.

Fig. 5 is a fragmentary plan view, looking opposite to the line of view in Fig. 1, showing one of the joints of the toggle with the mandrel proper, portions being shown in section.

The mandrel proper is of rectangular form, and comprises angular or L-shaped corner pieces or sections 1 formed of sheet metal, and having their wings arranged at right angles with one another, and the mandrel further includes side plates 2 and end plates 3 overlapping the long and short wings, respectively, of the corner pieces or sections 1. The side and end plates are at the inner side of the corner pieces, and the corner pieces provide the form on which the box is made or worked on, the side and end plates filling the spaces between the corner pieces. The corner pieces are slidably connected with the side and end plates, thus permitting the mandrel to be adjusted to different lengths and widths, and in order to slidably connect the parts or sections of the mandrel in an effective and substantial manner, the edges of the side and end plates are bent inwardly to form beads 4, which serve to stiffen the plates, and, if desired, reinforcing wires 5 can be located within the beads 4. The edges of the wings of the corner pieces 1 are bent back inwardly, as at 6, to provide rounded slideways or grooves for receiving the beads 4, and the lips 6 formed by the bending back of the corner pieces, are preferably reflexed, as at 7, adjacent to the beads 4, thus stiffening the lips 6 and making the structure more substantial and rigid. In this manner, the edges of the parts of the mandrel are rounded, and the edges of the sheet metal are bent back inwardly out of the way to stiffen the parts, and to also make the sliding connections stronger.

Socket members 8 can be secured within the angles of the corner pieces 1 for the reception of posts (not shown) to provide extensions for the corners of the mandrel, but as this feature is well known, it need not be considered further.

The mounting for the mandrel includes strips or plates 9 riveted or otherwise secured to the inner surfaces of the side and end plates 2 and 3, each of said plates 9 being provided with an inwardly projecting lug 10, and two pairs of guide and supporting bars 11 having their outer ends seated within notches or seats 12 in the lugs 10 and secured thereto by means of rivets 13 extending through said lugs. One pair of bars 11 is located longitudinally from one end plate to the other, while the other pair of bars 11 is located transversely, extending from one side plate 2 to the other, so that the two pairs of bars 11 cross one another, the bars of each pair overlap one another longitudinally for sliding adjustment. The bars 11 are rigidly secured to the side and end plates, through the medium of the lugs 10 and plates 9, in order to assist in supporting the mandrel and holding it firmly in position.

In order to support and guide the bars 11, a supporting block 14 is provided at the center of the mandrel, one side of said block being provided with grooves or channels 15 extending across the face thereof for receiving the overlapping portions of the bars 11, one groove 15 being deeper than the other, as shown in Fig. 2, in order that the bars 11 can cross within the block, it being noted that the bars 11 are in different planes. The bars fit snugly in the grooves or channels 15, thus preventing transverse displacement of said bars, although permitting longitudinal sliding movement thereof. A plate 16 is secured to said side of the block 14 over the grooves 15 by means of screws 17 or the like, thereby retaining the bars 11 within the grooves with a snug fit, yet permitting longitudinal sliding movement of said bars.

This plate 16 is carried by a yoke 18 that has a portion 19 for attachment to a supporting standard or the like. The yoke 18 thus supports the plate 16 and block 14, which in turn support the bars 11 and other parts that extend from the block 14 to the mandrel proper.

As a means for facilitating the adjustment of the mandrel and for clamping or holding the parts in position after adjustment is made, that side of the block 14 opposite to the grooves 15 has a boss 20 provided with stud 21 into which a clamping screw 22 is threaded. Two pairs of crossed levers 23 are mounted on the stud 21, each lever having an opening 24 between its ends to receive the stud 21, and toggle links 25 are pivoted to the levers 23 by means of rivets or the like, and converge to and engage the rivets 13 at those sides of the lugs 10 opposite to the bars 11, as seen in Fig. 2. The levers 23 that are connected to the side plates 2 are of shorter length than the levers

23 that are connected to the end-plates 3, in proportion to the distances between said plates, and it will be understood that between each pair of plates 2 and 3, there is a pair of crossed toggled levers 23 having their ends connected by links 25 with the respective plates.

To adjust the mandrel, the screw 22 is loosened, which may be readily turned by the thumb and fingers, and this loosens the levers 23. Then, the end plates 3 can be moved toward and away from one another to adjust the mandrel to the length desired, within the limits of the adjustment permitted, and likewise the side plates 2 can be moved toward and away from one another to adjust the mandrel to the desired width. It will be noted that the toggle mechanism constrains the plates of each pair to move equal distances from the center of the mandrel, whereby the mandrel in all adjustments is disposed concentric with the supporting means. Furthermore, the side and end plates can be adjusted independently without interference or destroying the adjustment of either. Thus, when the side plates 2 are adjusted, the bars 11 and toggle thereof will move, and the plates 3 and their bars 11 and toggle remain stationary, whereas when the plates 3 are adjusted, the plates 2 will remain stationary with their bars 11. Thus, the bars 11 of each pair of plates prevent said plates from moving endwise when adjustments are being made, while the toggle mechanism constrains the plates of each pair to move the same distance from the center. Together, the bars 11 and toggle devices support the mandrel from the interior thereof in a firm and substantial manner and when the screw 22 is tightened after adjustments have been made, the levers 23 will be clamped on the stud 21, thereby preventing further movement of the parts of the mandrel, and holding them in their adjusted position.

Having thus described the invention, what is claimed as new is:—

1. A mandrel having opposite adjustable portions movable toward and away from one another, a supporting member located centrally within the mandrel, and a toggle device including a pair of crossed levers pivotally connected at their point of crossing to said member, and links connecting said levers and portions, so as to constrain said portions for simultaneous movement toward and away from said member.

2. A mandrel embodying two pairs of opposite plates, a supporting member located centrally within the mandrel, and an independent toggle device connecting each pair of opposite plates with the supporting member, to constrain the corresponding pair of plates for simultaneous movement toward and away from said member, and providing

for individual adjustment of each pair of plates independently of the other pair of plates.

3. A mandrel having pairs of opposite plates, a supporting member located centrally within the mandrel, two pairs of crossed levers pivoted at their point of crossing to said member, and links connecting each pair of levers with the plates of the corresponding pair to provide a toggle device for constraining said plates for simultaneous movement toward and away from said member.

4. A mandrel having pairs of opposite plates, corner pieces slidably connecting them, a supporting member located centrally within the mandrel, pairs of overlapping bars secured to said plates, and slideable in said member in crossed relation, and a toggle device between each pair of plates and said member for constraining said plates

for simultaneous movement toward and away from said member, and means for clamping some of said parts to said member to hold said plates in position.

5. A mandrel having side and end plates, corner pieces slidably engaging them, a central block having crossed channels and a stud, pairs of overlapping bars secured to said plates and fitting slidably in said channels, pairs of crossed toggle levers mounted on said stud, toggle links connected to said levers and the respective side and end plates, and clamping means carried by said stud for clamping said levers thereon.

In testimony whereof I have signed my name to this specification in the presence of two subscribing witnesses.

MOSES B. DISKIN.
